UNITED STATES PATENT OFFICE.

EARL C. BACON, OF INDIANAPOLIS, INDIANA, ASSIGNOR, BY DIRECT AND MESNE ASSIGNMENTS, TO THE FLASH LIGHT SIGN COMPANY, OF CONNELSVILLE, INDIANA, A CORPORATION OF INDIANA.

ELECTRICAL SWITCH.

No. 822,036.

Specification of Letters Patent.

Patented May 29, 1906.

Application filed December 8, 1904. Serial No. 236,042.

To all whom it may concern:

Be it known that I, EARL C. BACON, a citizen of the United States of America, and a resident of Indianapolis, county of Marion, State of Indiana, have invented certain new and useful Improvements in Electrical Switches, of which the following is a specification.

The object of my invention is an electrical switch for directing the current from one set of lamps into another, which is simple in construction and in which the contacts are made and broken quickly. This object is attained by the means described in the specification and illustrated in the accompanying drawings, in which—

Figure 1 is a front elevation of a switch embodying my invention, the lights being shown diagrammatically. Fig. 2 is a sectional view taken upon line *v v* of Fig. 1. Fig. 3 is a view similar to that shown in Fig. 1, but with the parts in the opposite position.

Referring to the parts, a lever *A*, having a short metallic arm *a* and a long arm consisting of two parts *a'* and *a''*, is pivoted at *a³* upon an insulated bracket *B*. Arm *a'* has insulation *a⁴* adjacent to arm *a*. Parts *a'* and *a''* are pivoted at *a⁵*. A straight spring *C* passes through the pivot *a⁵* and is confined at its upper end between posts *a⁶* and *a⁷*, secured to the part *a'*, and at its lower end is confined between studs *a⁸* and *a⁹*, secured to parts *a''*, so that the tendency of the spring is to hold the parts *a'* *a''* in alinement with each other. At its lower end, part *a''* carries contact-pieces *D* and *D'* and has a lower projecting lug *a¹⁰*. At the lower end of the arm *a''*, adjacent to contact-pieces *D* and *D'*, are terminals *E*, *E'*, *E''*, and *E³*. Between the terminals *E'* and *E³* is located a rigid stud *e*, which is contacted by the lug *a¹⁰*.

Pivoted to the outer end of arm *a* is a metal link *G*, made, preferably, of a metal having a large coefficient of linear expansion in increasing degrees of temperature. Link *G* is secured at its lower end to a post *g*. The positive wire *g'* of the electric circuit is connected to post *g*. Surrounding arm *a* and insulated from it is a coil of fine wire *g²*, one end of which is connected to link *G* and the other end of which is connected to pivot *a³* and from there passes to wire *g³*, which leads to

the terminal *E*. Terminal *E'* is connected by wire *g⁴* to series *H* of the lamps.

Leading from post *g* is a wire *g⁵*, which is connected to terminal *E²*. From terminal *E³* a wire *g⁶* leads into series *H'* of the lamps.

At normal temperature the length of the link *G* is such that it holds the contact-piece *D* against terminals *E* *E'*. The current through wire *g'* then passes through link *G*, coil *g²*, wire *g³*, terminal *E*, contact-piece *D*, terminal *E'*, and wire *g⁴*, through the set *H* of lamps, and thence through wire *g⁷* to the negative pole of the battery or energizing source. The current passing through the coil *g²* heats up the metallic arm *a*. The heat is conveyed by contact to the link *G*, lengthens the same, and causes it to swing the lever *A* to the position shown in Fig. 1. The stud *e* being contacted by the lug *a¹⁰* holds the contact-piece *D* in communication with the terminals *E* *E'* until the buckling of the arms *a'* *a''* draws the lug *a¹⁰* above stud *e*. Spring *C* then quickly throws the arm *a''* over, bringing the contact-piece *D'* against terminals *E²* *E³*. The current then instead of going through the link *G* and the coil *g²* passes through the lesser resistance offered by wire *g⁶*, terminals *E²* *E³*, contact-piece *D'*, and wire *g⁷*, through the lamps *H'*. The cutting off of the current from coil *g²* causes the arm *a* and the link *G* to become cooled. The link then contracts and throws the lever *a'* and *a''* in the position shown in Fig. 3. Again, in this operation the stud *e* contacting the lug *a¹⁰* holds the contact-piece *D* against terminals *E²* *E³* until the buckling has carried the lug *a¹⁰* up above stud *e*, when the spring *C* will throw the contact-piece *D'* quickly again into contact with terminals *E* *E'*. Thus the switch is thrown alternately, quickly, and automatically to bring first contact-piece *D* in contact with terminals *E* *E'* and then contact-piece *D'* in communication with terminals *E²* *E³*.

The heat generated in the arm *a* and conveyed by contact to the arm *G* is sufficient to cause the arm *G* to lengthen enough to throw the arms *a'* *a''* from the position shown in Fig. 1 to that shown in Fig. 3. This is true, first, because the arm *a* is made very much shorter than the combined lengths of the arms *a'* *a''*, so that a small movement in

the arm a amounts to a considerable movement at the end of arm a^2 ; secondly, the contact of the tooth a^1 with the stud e is not deep, so that it takes but a small movement 5 of the arm a^2 to move it from one side to the other of the stud e . Moreover, link G is made of a metal having a large coefficient of expansion, so that it does not take much of a change in temperature to change its length 10 sufficient to effect the movement desired.

What I claim is—

1. In combination a lever having an arm upon each side of its pivot-point, a link of a material expanded by heat connected at one 15 end to one arm of the lever and secured in place at the other end, contact-pieces carried by the other arm of the lever, terminals adjacent to the contact-pieces, independent sets of lamps one in communication with one set 20 of terminals, the other in communication with the other set of terminals, a divided feed-wire one branch of which leads to the link and the other to one set of terminals, a resistance in communication with the link to 25 be heated by the current therefrom and to convey the heat to the link, and a wire leading from the resistance to the other set of terminals.
2. In combination a lever having an arm 30 upon each side of its pivot-point, one of its arms consisting of two parts pivoted together, a spring to hold the parts normally in alignment with each other, a lug at the lower end of the pivoted arm, a metallic link of a material expanded by heat connected at one end 35 to the other arm of the lever and secured in

place at its other end, contact-pieces carried by the first arm of the lever, terminals adjacent to the contact-pieces, a stud between the terminals for contacting the lug, independent sets of lamps one in communication with one set of terminals, the other in communication with the other set of terminals, a divided feed-wire, one branch of which leads to the link and the other to one of the sets of terminals, a resistance in communication with the link to be heated by the current therefrom and to convey the heat to link, and a wire leading from the resistance to the other set of terminals. 40

3. In combination a lever consisting of a short metallic arm and a long arm, a pivot between the arms, an insulation in the longer arm, contact-pieces at the lower end of the longer arm, terminals upon each side of the 45 longer arm adjacent to the contact-pieces, a link connected at one end to the metallic arm and at the other end secured to a pivot-post, a resistance surrounding the metallic arm and insulated therefrom and electrically connected to the link, a wire leading from the other end of the resistance to one of the terminals, a feed-wire leading to the binding-post of the link, a feed-wire leading from the post to the second set of terminals, two sets 50 of lamps one in communication with one set of terminals, and the other in communication with the other set of terminals.

EARL C. BACON.
